(57) CLAIM

The ornamental design for a cap, as shown and described.

DESCRIPTION

FIG. 1 is a perspective view of a cap showing the design; FIG. 2 is a front elevation view thereof; FIG. 3 is a top plan view thereof; FIG. 4 is a left side elevation view thereof, the right side being a mirror image; FIG. 5 is a rear elevation view thereof; and, FIG. 6 is a bottom plan view thereof.

The broken lines in the drawings are included for the purpose of showing portions of the cap that form no part of the claimed design.
